CLAIM

The ornamental design for an illuminating magnifier apparatus, substantially as shown and described.

DESCRIPTION

FIG. 1 is a top perspective view of the illuminating magnifier employing my new design;

FIG. 2 is a top view of FIG. 1;

FIG. 3 is a bottom perspective exploded view of FIG. 1;

FIG. 4 is a bottom perspective assembled view of FIG. 3;

FIG. 5 is a left side view of FIG. 1;

FIG. 6 is a right side view of FIG. 1;

FIG. 7 is a front end view of FIG. 1; and,

FIG. 8 is a rear end view of FIG. 1.

The broken line showing of environment in the drawings is included for the purpose of illustrating only and forms no part of the claimed design.
